MOLDED COMPOSITION TERMINAL FOR A CABLE

Henry W. Yarick, Jr., Glendale, Calif., assignor to The Garrett Corporation, Los Angeles, Calif., a corporation of California

Application December 24, 1958, Serial No. 53,902

Term of patent 14 years

(Cl. D26—1)

Fig.1.

Fig.2.

Fig. 1 is a top plan view of a molded composition terminal for a cable, showing my new design; and

Fig. 2 is a side elevational view, the opposite side being substantially a mirror image thereof.

The dominant features of my new design are shown in solid lines in the drawing.

I claim:

The ornamental design for a molded composition terminal for a cable, as shown and described.
